UNITED STATES PATENT OFFICE.

CHARLOTTE E. ALLSPACH, OF UBEE, INDIANA.

CHICKEN-BROODER.

1,257,063.

Specification of Letters Patent. Patented Feb. 19, 1918.

Application filed October 18, 1917. Serial No. 197,285.

To all whom it may concern:

Be it known that I, CHARLOTTE E. ALLSPACH, a citizen of the United States, residing at Ubee, in the county of Huntington and State of Indiana, have invented certain new and useful Improvements in Chicken-Brooders; and I do hereby declare the following to be a full, clear, and exact description of the invention, such as will enable others skilled in the art to which it appertains to make and use the same.

This invention has for its object to provide an improved chicken brooder, which shall be efficient in use and simple and exceptionally inexpensive in construction.

Another object is the provision of a chicken brooder consisting of a minimum number of parts which may be readily disassembled to facilitate thorough cleansing of the interior.

With these and other objects in view, the invention consists in the novel construction, combination and arrangement of parts as will be hereinafter specifically described, claimed and illustrated in the accompanying drawing, in which:

Figure 1 represents a front elevation of the brooder,

Fig. 2 represents a bottom plan view of the frusto-conical cover or roof, partly in section, and

Fig. 3 represents a vertical sectional view through the brooder in the plane of the entrance opening.

Referring to the drawing in detail, wherein similar reference numerals designate corresponding parts throughout the several views, the numeral 5 indicates, generally the housing of the brooder, which consists of a circular floor 6, cylindrical body 7 and frusto-conical top or cover 8. These parts of the housing are preferably constructed of sheet metal of adequate thickness to lend requisite strength and rigidity to the structure and the side wall or body 7 is permanently attached to the floor 6, the peripheral edge of which latter projects beyond the outer surface of the side wall 7. The front portion of the side wall 7 is formed with an entrance opening 9 of adequate size to permit the chickens to pass therethrough, and the upper part of the side wall is provided with an adequate number of ventilating ports 10.

The upper terminal of the cover or top 8 is truncated, as indicated at 11, and the lower portion is of such diameter as to telescopically receive the upper edge of the cylindrical side wall 7. A plurality of angular supporting members 12 are secured to the inside and adjacent the lower edge of the top 8, which supports the latter in spaced relation to the upper edge of the cylindrical side wall 7, thereby providing an additional ventilating opening 13.

The top 8 is removably supported upon the side wall 7 in order that it may be conveniently removed to permit the interior of the lower part of the housing to be thoroughly cleansed.

A supporting post 14 is secured to the truncated upper terminal 11 of the top by a headed fastener 15, and the lower terminal of the post projects downwardly toward the floor.

The quills of a group or tuft of feathers 16 are secured to the lower terminal of the post 14 by an elastic band 17, which may be readily removed to permit of the removal of the feathers 16. The feathers are arranged so as to form a supplemental roof to the lower part of the housing for protecting the chickens located therein.

What I claim is:

1. A chicken brooder including a cylindrical side wall provided with entrance and ventilating openings, a floor secured thereto, a frusto-conical cover, supporting arms carried by the cover removably engaged with the upper edge of the cylindrical side wall, a post secured to the truncated terminal of the top, and a tuft of feathers carried by and depending from the post.

2. A chicken brooder including a cylindrical side wall, a floor secured thereto, a frusto-conical top removably supported upon the side wall, a depending post carried by the truncated terminal of the top, and a tuft of feathers carried by the lower terminal of the post and disposed centrally within the side walls.

In testimony whereof I affix my signature in presence of two witnesses.

CHARLOTTE E. ALLSPACH.
